UNITED STATES PATENT OFFICE.

JOSEPH FOLLMER, OF DENVER, COLORADO.

BENCH VISE.

Application filed February 20, 1926. Serial No. 89,730.

This invention relates to bench vises and particularly to vises mounted upon the bench and designed to be of particular value in such work as planing doors, sashes and the like.

A further object of is to provide a device of this character in which all permanent members of the vise are flush with the top of the bench so as to form no obstruction to the ordinary use of the bench.

Another object is to provide a vise of this character comprising one element adapted to be applied to the edge of the bench and having a plurality of sockets and another screw shifted element adjustable toward or from the first named element and having a single socket, and provide work engaging jaws having shanks insertible in said sockets, these jaws being removable from the two elements when desired.

Other objects will appear in the course of the following description.

My invention is illustrated in the accompanying drawings wherein:—

25 Figure 1 is a fragmentary elevation of a carpenter's bench with my device applied thereto;

Figure 2 is a top plan view of the structure shown in Figure 1;

30 Figure 3 is a section on the line 3—3 of Figure 4;

Figure 4 is an enlarged fragmentary top plan view of a portion of the structure shown in Figure 2;

35 Figure 5 is an enlarged section on the line 5—5 of Figure 2;

Figure 6 is an enlarged section on the line 6—6 of Figure 2;

Figure 7 is an enlarged section on the line 40 7—7 of Figure 2;

Figure 8 is a front elevation of one of the jaws and its shank; and

Figure 9 is a side elevation of the same.

Referring to these drawings and particularly to Figures 1, 2 and 4, it will be seen that one element of my vise comprises a metallic strip or other strip designated 10, having any desired length and adapted to be held against the edge face of the top of a carpenter's bench, designated B, by means of screws 11 having their heads disposed in countersinks in the strip 10. The inner face of the strip 10 is formed with recesses

50 or sockets 12 which open onto the inner face of the strip 10 and, therefore, the edge of

the table or bench B constitutes the fourth wall of each socket.

The other element of my vise comprises a head nut 13 which is held against one end face of the bench by means of the screw 14 60 and by means of the U-shaped strap 15 which is bolted to the bench and may be countersunk therein, this strap embracing the head nut and being bolted thereto, as illustrated in Figure 7. The head nut is 65 screw threaded for the screw 16 having a handle 17 at one end, the opposite end having swiveled engagement with a head 18. This head is formed with a socket 19 extending entirely through the head. The inner face 70 of this head 18 is formed with a rib 20, T-shaped in cross section to engage in the guide recess 21 formed in one face of the member 15.

Operating in the sockets 12 and in the 75 socket 19 are the jaw carrying posts or shanks 22, each formed at its upper end with an enlargement constituting a jaw and designated 23, this enlargement being roughened, knurled or otherwise formed 80 upon one face as shown in Figures 8 and 9. The lower end of each post is formed with an inclined face 24 and riveted to this inclined face is a spring 25 which, when the post is inserted within a socket, acts 85 to cause a binding action which will hold the post within the socket.

The use of this device will be obvious from what has gone before. One of the posts may be inserted in any one of the sockets 12 90 and disposed nearer to or further from the movable head 18 as desired. One of the posts 22 is also to be disposed in the socket in the head 18. Then the article to be clamped is disposed upon the bench in a position to be engaged between the two jaws formed by the post and then the screw 16 is turned to shift the head 18 toward the member 10 until the article is clamped firmly upon the bench.

This device may be applied to any existing work bench and necessitates but very little cutting of the bench or change therein as it is to be applied on the extreme left hand of the bench. It is particularly simple and it is very readily handled. It has been found to be particularly effective for such work as planing doors, sashes and the like. The posts when not in use can be pushed down into the socket or taken out entirely, 110

as desired, it being noted that each socket at its upper end has an enlarged portion into which the enlarged head of the post fits when depressed.

5 I claim:—

1. A bench clamp comprising a member having vertical sockets extending therethrough and having means whereby it may be attached to the edge of a carpenter's bench, a head nut having a screw-threaded opening, a supporting member for the head nut adapted to engage the edge of the bench, a screw passing through the opening in the head nut and having a handle, a head swiveled to the other end of the screw and having interlocking sliding engagement with said head nut supporting member, the head on the screw having a vertically extending socket therethrough, and jaw members each including a post adapted to extend into said sockets and being removable therefrom.
2. The combination with a carpenter's bench, of a vise comprising a strip attached to one edge of the bench and extending longitudinally therealong flush with the upper face thereof and having a plurality of sockets extending vertically through the strip and at spaced distances, a head nut mounted upon the bench at right angles to said strip, a member engaging the head nut with the bench, the member having a longitudinally extending groove upon the face of said member parallel to the strip, a screw passing through the head nut and having a handle at one end and a head swiveled to the other end of the screw and having a vertically extending socket, the head having a rib slidingly engaging said groove in said head nut supporting member, and jaw supporting posts insertible into any one of said sockets.

3. The combination with a carpenter's bench, of a vise comprising a member attached to one edge of the bench and having a plurality of vertical sockets extending entirely through said member, a head nut disposed against one end of the bench and having a screw threaded opening, a clamping member for the head nut embracing the same and extending longitudinally along one edge of the bench and embracing the edge of the bench, said member having upon one face a slot which is T-shaped in cross section, a screw passing through the

opening of the head nut and having a handle at one end and a head swiveled to the other end of the screw and having a T-shaped groove engageable in said recess, the head having a socket extending vertically therethrough, and a plurality of jaw carrying posts engageable in said sockets.

4. The combination with a carpenter's bench, of a vise comprising a member attached to one edge of the bench and having a plurality of vertical sockets extending entirely through said member, a head nut disposed against one end of the bench and having a screw threaded opening, a clamping member for the head nut embracing the same and extending longitudinally along one edge of the bench and embracing the edge of the bench, said member having upon one face a slot which is T-shaped in cross section, a screw passing through the opening of the head nut and having a handle at one end and a head swiveled to the other end of the screw and having a T-shaped groove engageable in said recess, the head having a socket extending vertically therethrough, and a plurality of jaw carrying posts engageable in said sockets.

5. A bench clamp comprising a strip having vertical sockets extending therethrough on its inner face and having means whereby it may be attached to the edge of a carpenter's bench, a head nut having a screw threaded opening, a clamp therefor U-shaped in vertical section to embrace said head and embrace the edge of the bench and having a groove upon its side face, a screw passing through the opening in the head nut and having a handle at one end, a head swiveled to the other end of the screw and having interlocking sliding engagement with the groove and said clamping member, said head having a vertically extending socket therethrough, and jaw members each having a head, and a post adapted to extend into said sockets and to be vertically adjustable therein.

In testimony whereof I hereunto affix my signature.

JOSEPH FOLLMER.
